UNITED STATES PATENT OFFICE

GEORGE W. BOWEN, OF AUBURN, NEW YORK

TURNTABLE

Application filed December 10, 1927. Serial No. 239,135.

This invention relates to a new and improved turn-table, particularly designed for use for automobiles.

Hitherto turn-tables of this character have been difficult to operate because of the fact that the means employed to keep the table centered have been such as to cause a considerable amount of friction with the resultant drag on the operation of the table.

These tables are usually made to rotate on a series of rollers, which rollers, in turn, travel around a circular track.

In order to keep the rollers in position on the track an outside circumferential flange is usually provided at the edge of the track. The result of this construction is that the rollers will bear against this flange and be in frictional contact therewith.

The main object of my invention is to provide a centering means for the table which will be positive in action and yet which will accomplish the desired result with the minimum amount of friction and hindrance to the operation of the table.

Another object is to provide a simple turn-table and one which can be installed with ease and which will have a considerably longer operative life than tables now known to the art.

Other objects and advantages relate to the size, shape and arrangement of parts, all as will more fully appear from the following description taken in connection with the accompanying drawings in which:

Figure 1 is a top plan view, partially broken away, of my turn-table.

Figure 2 is a section on line 2-2 of Figure 5.

Figure 3 is a section on line 3-3 of Figure 1.

Figure 4 is a section on line 4-4 of Figure 1.

Figure 5 is a section on line 5-5 of Figure 1.

Figure 6 is a section similar to Figure 5 showing a modified form of my centering device.

Figure 7 is a sectional view similar to Figure 6 showing another modified form of my device.

Figure 8 is a sectional view through a portion of the track showing a lapped joint.

Figure 9 is a perspective view of a booster plate used in connection with the rollers.

Figure 10 is a perspective view of the booster plate used at the center bearing.

My device consists of a pit —1— made of appropriate material, but preferably cement.

This pit —1— is circular in form and is countersunk into the ground or into the floor of a garage a sufficient distance so that when turn-table —2— is in position the upper surface or floor —3— of turn-table —2— will be slightly above the ground or the floor of the garage.

This pit —1— is preferably dished in shape with its lowest point at the center thereof so that water getting into the pit will collect at the center from where it can be carried off by a drain —4—.

In the preferred form of my pit I provide a trough —5— which is placed circumferentially around the floor of the pit in juxtaposition to the outside periphery of track —6— hereinafter to be described.

Any moisture collecting in trough —5— will be carried off through a branch drain —24— leading into main drain —4—.

At the central portion of pit —1— I provide a raised portion —7— in the center of the top of which is positioned a lower bearing member —8— having a recess —9— in its upper surface for the reception of ball —10—. An upper bearing member —11— having a recess —12— in its lower surface for positioning on the top of ball —10— is circular in form and has on the upper surface thereof a plurality of radially extending V-shaped flanges —13— which are adapted to receive the ends of stringers —14—.

A circular track —6—, preferably of steel and with lapped joints, —40—, is positioned in the bottom of pit —1— in spaced relation to raised portion —7— and the outside edge —15— of pit —1—. The track —6— has attached to its outside periphery a plurality of angle irons —16— by bolts —17— or other convenient means and these angle irons —16— are countersunk into the material of

which pit —1— is constructed so as to lock track —6— permanently in position.

I provide a plurality of stringers —14—, in this case sixteen, which have one end placed on the upper surface of member —11— and which extend radially therefrom in spaced relation to a position adjacent to the outside wall —15— of pit —1—, a circular plate —33— of the same diameter as member —11— being placed over the ends of all the stringers —14— and being fastened to member —11— by means of bolts —43—, which bolts —43— pass through stringers —14— to fasten the same in position.

I provide a plurality of rollers —18—, one of which is secured to the bottom face of each stringer —14—, in such a position that it will register upon the track —6—. These rollers —18—, as may be seen in Figure 4, are preferably of the usual type which carry roller bearings, and they consist of a body member —19—, a wheel —20—, a shaft —21— and the usual rollers —22— interposed between shaft —21— and wheel —20—.

Rollers —18— are secured to stringers —14— by means of bolts —23— or other convenient means.

To provide a floor surface for the turn-table and to secure stringers —14— in fixed spaced relation I provide floor boards —25— which are secured by bolts —26— or other convenient means to stringers —14—.

Floor boards —25— are of sufficient length so that each one is secured to three of the stringers —14—. As will be seen from Figure 1 floor boards —25— are of such shapes and forms as to cover the whole of the inside diameter of pit —1—. Floor boards —25— are preferably spaced from each other radially so that the water may drain between them into pit —1— and be carried off through drain —4—.

In order that turn-table —2— may be locked in position, except when it is desired to rotate the same, I provide latches —27— on opposite sides of turn-table —2— and secured to the upper surface thereof by screws —28— or other convenient means, this latch —27— consisting of a bottom plate —29— and a latch-member —30— pivoted thereon. Latch-member —30— is of sufficient length to extend outwardly over the top of the outside rim —15— of pit —1— and at a selected position on the upper face of pit —1—, I provide a keeper —31— secured in the material of which pit —1— is constructed.

The part of keeper —31— which extends above pit —1— is rounded in shape and carries a notch —32— on its top surface which notch —32— is of a size and shape to receive the end of latch —30—.

The outside edges of keeper —31— are flush with the upper surface of pit —1— so

that when the turn-table —2— is being rotated and the latch —30— in its lowered position, the latch —30— when it strikes keeper —31— will ride upward thereon and drop into slot —32— to lock the turn-table —2— in position.

In Figure 6 I show a slight modification of my device in that instead of having a large upper bearing member —11— which is designed to receive the ends of stringers —14—, I provide a smaller upper bearing member —34— which is circular in shape and which has on its under surface a recess —35— for the reception of ball —10—.

On top of member —34— I provide a circular plate —36— upon which rests the ends of stringers —14—. A top plate —37— of the same size and shape as plate —36— is positioned on top of stringers —14— and the plates —34— and —37— are then fastened together by means of bolts —38— which pass through stringers —14—, upper plates —34— and —37— being also fastened to member —34— by means of bolts —39— which pass through plates —34— and —37— and through stringers —14—.

The design of my device is such that when an automobile is in position on the turn-table and latches —30— in the open position, rollers —18— will be held in position on track —6— because of the fact that the ball-bearing formed by members —7— and —11— and ball —10— will prevent any radial movement of turn-table —2—.

At the same time members —7—, —11— and ball —10— will not offer any appreciable resistance to the rotation of turn-table —2— inasmuch as the weight of the automobile will be applied to the upper surface of turn-table —2— at the outer edges thereof and practically the whole load will be borne by rollers —18— and track —6—, there being little if any, pressure on ball —10— so that it will be asked only to keep the turn-table —2— from radial movement.

In Figure 7 I illustrate a modified form of my device which is used when it is desired to have my turn-table adjustable with relation to the surrounding road-bed. In this form I provide a circular booster plate —41— which is interposed between the bearing member —34— and plate —36—. This booster plate —41— is provided with holes —45— around its periphery to permit the passage through it of bolts —39—. It also is provided with a centrally located hole —46— to permit the passage of eye bolt —44—. Eye bolt —44— passes through a hole —48— in top plate —37— and through a hole —49— in plate —36— and thence through a hole —46— in booster plate —41— and is threaded into top bearing member —34—. Booster plates —42—, of the same thickness as booster plate —41—, are interposed between each of the rollers —18— and stringers —14—, booster

plates —42— being provided with spaced holes —47— to allow the passage of bolts —28—. It will be seen that when it is desired to change the relation of the upper surfaces of floor —3— to the surrounding road-bed that the whole apparatus may be lifted from position by means of eye bolt —44—, and one or more sets of booster plates —41— and —42— may be placed in the position just described to accomplish the required raising of the apparatus.

Figure 7 also is used to illustrate the method of installation of my device when the contour of the road-bed in which it is to be installed requires that the device be positioned at an angle to the perpendicular. In this case the lower bearing member —8— is preferably positioned with the ball recess —35— so that its outside edges are in a horizontal position.

It will be understood that the size and shape of recesses —35— and —12— are so proportioned, with reference to ball —10—, that the apparatus will be held from lateral movement when installed in this inclined position.

The ability to install the apparatus on a grade is of a great advantage because very frequently the road-bed in which it is to be installed is on a grade which makes it difficult, if not impossible, to install the ordinary type of turn-table.

It will also be understood that metal may be used throughout instead of wood if desired, and although I have shown and described a specific structure and form of part as illustrative of an embodiment of my invention, I do not desire to restrict myself to that exact shape, form or relation of parts, as various changes may be made within the scope of the appended claims.

40 I claim:

1. In a device of the class described, a platform having a central spider with radially extending arms, radially extending supporting members attached to said spider arms, each supporting member having a roller attached to the underside thereof in spaced relation to the spider, a circular track supporting the rollers, a depression in the bottom face of the spider for the reception of a ball, and constituting an upper bearing for the ball, a lower bearing for the ball, a ball in the bearing, and a floor attached to the upper surfaces of the supporting members to hold them in spaced relation.

53 2. In a device of the class described, a platform having a central spider with radially extending arms, radially extending supporting members attached to said spider arms, each supporting member having a roller attached to the underside thereof in spaced relation to the spider, a circular track supporting the rollers, a depression in the bottom face of the spider for the reception of a ball, and constituting an upper bearing for the ball, a lower bearing for the ball, a ball in the

bearing, and a floor attached to the upper surfaces of the supporting members to hold them in spaced relation, the upper surface of said floor being in a plane disposed above the plane of the adjacent road bed.

3. In a device of the class described, a platform having a central spider with radially extending arms, radially extending supporting members attached to said spider arms, each supporting member having a roller attached to the underside thereof in spaced relation to the spider, a circular track having lapped joints supporting the rollers, a depression in the bottom face of the spider for the reception of a ball, and constituting an upper bearing for the ball, a lower bearing for the ball, a ball in the bearing, and a floor attached to the upper surfaces of the supporting members to hold them in spaced relation, the upper surface of said floor being in a plane disposed above the plane of the adjacent road bed.

4. In a device of the class described, a platform having a central spider with radially extending arms, radially extending supporting members attached to said spider arms, each supporting member having a roller attached to the underside thereof in spaced relation to the spider, a circular track having lapped joints supporting the rollers, a depression in the bottom face of the spider for the reception of a ball, and constituting an upper bearing for the ball, a lower bearing for the ball, a ball in the bearing, and a floor attached to the upper surfaces of the supporting members to hold them in spaced relation, the upper surface of said floor being in a plane disposed above the plane of the adjacent road bed.

5. In a device of the class described, a platform having a central spider with radially extending arms, radially extending supporting members attached to said spider arms, each supporting member having a roller attached to the underside thereof in spaced relation to the spider, a circular track supporting the rollers, a depression in the bottom face of the spider for the reception of a ball, and constituting an upper bearing for the ball, a lower bearing for the ball, a ball in the bearing, and a floor attached to the upper surfaces of the supporting members to hold them in spaced relation, the upper bearing and the lower bearing for the ball both being of a size and shape to permit the installation of the device with the upper surface of the floor in a plane other than normal to a vertical line drawn through the center of the ball.

6. In a device of the class described, a platform having a central plate, radially extending supporting members attached to the upper side of said plate, each supporting member having a roller attached to the underside thereof in spaced relation to the cen-

tral plate, a circular track supporting the rollers, a depression in the bottom face of the central plate for the reception of a ball, and constituting an upper bearing for the ball, a lower bearing for the ball, a ball in the bearing; a floor attached to the upper surfaces of the supporting members to hold them in spaced relation, and means for increasing the vertical distance between the upper surface of the floor and the upper surface of the circular track.

7. In a device of the class described, a platform having a supporting plate, radially extending supporting members attached to said plate in spaced relation, each supporting member having a roller attached to the underside thereof in spaced relation to the plate, a circular track supporting the rollers, a depression in the bottom face of the plate for the reception of a ball and constituting an upper bearing for the ball, a lower bearing for the ball, a ball in the bearing, and flooring attached to the upper surfaces of the supporting members to hold them in spaced relation.

In witness whereof I have hereunto set my hand this 30th day of November, 1927.

GEORGE W. BOWEN.
